CLAIM

The ornamental design for a multi-function switch, as shown and described.

DESCRIPTION

FIG. 1 is a perspective view of a multi-function switch showing, my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is, a top plan view thereof; and,

FIG. 8 is a bottom plan, view thereof.

The broken lines in the figures illustrate portions of the multi-function switch that form no part, of the claimed design.
